James L. Lausa, Park Forest, Ill., assignor to Johns-Manville Corporation, New York, N.Y., a corporation of New York

Filed Aug. 2, 1961, Ser. No. 66,169

Term of patent 14 years

(Cl. D74—1)

FIG. 2.

FIG. 3.

FIG. 4.

FIG. 5.

FIG. 1 is a front perspective view of a tape dispenser showing my new design;

FIG. 2 is an end elevational view as seen from the left of FIG. 3;

FIG. 3 is a side elevational view;

FIG. 4 is an end elevational view as seen from the right of FIG. 3; and

FIG. 5 is a top plan view thereof.

The side of the dispenser opposite to that shown in FIGS. 1 and 3 is identical in appearance to that shown in FIG. 3.

I claim:

The ornamental design for a tape dispenser, substantially as shown and described.
